DES. 1926

Lawson C. Ives, of Hartford, Ct.

Letters Patent No. 1926 Dated March 29th 1864.

Design for a Thread Spool.

The schedule referred to in these Letters Patent and making part of the same.

To all whom it may concern:

Be it known that I, Lawson C. Ives, of the City of Hartford in the State of Connecticut, have invented a new and original shape or configuration of the article of manufacture commonly known as a spool, on which cotton, silk or linen thread is wound after being manufactured; and that the following description in connection with the drawings is a full, clear and exact description thereof. In the drawings.

Figure. First is a plan of the spool, and

Figure. Second, is a section through the axis of the same.

Spools on which thread of silk, cotton or linen is wound are a well known article of manufacture and are made by or for manufacturers of thread, and are sold either with or without thread wound upon them. The spools to which I refer are not those of large size which are usually termed bobbins and are employed in various stages of the manufacture of thread, but are those on which the thread is wound after it is finished and which are sold with the thread wound upon them to the consumer.

These spools are of various sizes, the size depending chiefly upon the number or fineness of the thread, and have usually tickets glued or pasted upon them, stating the number of the thread.

DES. 1926

2 the manufacturer's name, the length of thread on the spool, etc.

I have discovered that the tickets on ordinary spools commence to fall off by being rubbed up at their edges, and that the difficulty may to a great extent be obviated by affixing the ticket at the bottom of a recess in the end of the spool; when so affixed the edge of the ticket is protected by a rim of wood making a sort of frame around the ticket, and if the recess be deep enough, and I intend to make it so, the rim also prevents the face of the ticket from being rubbed or blurred.

My invention therefore consists in recessing the end of the spool in the manner shown clearly in the section, fig. 2, and the ticket a is then to be affixed at the bottom of the recess, which must be large enough to contain a ticket and deep enough to protect its edge, showing in fact a frame of wood around the ticket when the latter is in place as at b.b.

If the spool is to be ticketed on one end only, one recess is needed; if it is to be ticketed on both ends it should be recessed at both ends, and it may be recessed at both ends when only one end is ticketed.

The recess is to be formed by any proper tools or machinery and any manufacturer will be able to make the recess without further instruction after being told that a recess is needed either on one or both ends.

I claim as my own invention The new shape or configuration as herein described of the end or ends of a spool or manufactured article which is made for the purpose of having manufactured thread wound upon it.

In testimony whereof I have hereunto subscribed my name in the city of Hartford, on this Twenty fourth day of December A.D. one thousand eight hundred and sixty one, in presence of
Witnesses:

Myron Perry,
D.S. Lewis.

L.C. Ives.
